FIBER PULP REFINER

Daniel Manson Sutherland, Jr., Morrisville, Pa.,
assignor to Lionel M. Sutherland, Trenton,
N. J., and Douglas G. Sutherland, Morrisville,
Pa.

Application April 1, 1936, Serial No. 72,082

9 Claims. (Cl. 92—26)

My invention relates to the reduction and refining of fibrous materials, such as wood, leather, or cork, and especially to the treatment of "fiber pulp", consisting of fibrous particules in association with liquid, generally water. With sufficient water or the like, the aggregate or suspension itself behaves as a liquid, and can thus be more easily fed between the relatively moving refining surfaces or members by whose coaction 5 the fiber particles are reduced. In using relatively rotating discs as the refining members, both of them may actually revolve, either in opposite directions or in the same direction at different speeds; or only one may actually move, 10 while the other remains stationary.

In refining fibrous materials or pulp between relatively moving refining members, an important factor is the pressure between the acting surfaces. Comparatively little is known about 20 this factor; nor has it been controlled or gaged satisfactorily in practice. Some attrition mill refiners are operated with a fixed, dead-set working clearance or gap between the relatively rotating disc members, as illustrated in U. S. Letters Patent No. 1,984,869, December 18, 1934, 25 Farley and Brown; other refiners have the refining members held together by spring pressure, so as to yield and separate if extra large or hard fibrous particles come between the discs. Attempts have been made to determine the pressures between the discs by calculation from a 30 spring in compression at the end of one disc shaft; but this is not entirely equivalent to a direct pressure reading.

My invention allows of directly measuring and controlling the pressure between the refining surfaces, and of accurately gaging and regulating it according to the degree of refining of the fiber required for any particular paper or fiber board. 35 By such regulation, also, overload protection against damage to bearings or other parts of the refiner can be provided. A definite clearance for the refining action required can be readily set, maintained, and reproduced, so as to ensure 40 uniformity in refined pulp produced over an extended period of operation—or even on different occasions, between which the machine may have been used to produce an altogether different pulp. The refiner can be constructed, operated, 45 and maintained at relatively low cost.

Various other features and advantages of the invention will appear from the following description of species or forms of embodiment, and from the drawings. So far as novel, indeed, all features shown or described are of my invention. 50

In the drawings, Fig. I is a side view of a refiner conveniently adapted for the purposes of my invention, certain parts being broken away and omitted, and some parts being shown in vertical longitudinal section.

Fig. II is a plan view of the refiner, with certain parts removed or in horizontal section.

Fig. III is an end view from the right of Figs. I and II, with certain parts in cross-section as indicated by the line and arrows III—III in Fig. II.

Fig. IV is a view from the left of Figs. I and II, with certain parts in cross-section as indicated by the line and arrows IV—IV in Fig. II.

Fig. V is a fragmentary diagrammatic longitudinal vertical section through a pressure cylinder, such as shown in Fig. I, with certain added accessories.

Fig. VI is a fragmentary view similar to the corresponding portion of Fig. I, but showing a different revolving refining member.

Fig. VII shows a section taken as indicated by the line and arrows VII—VII in Fig. VI.

Fig. VIII is a view similar to Fig. VI, illustrating another modification; and,

Fig. IX is a view similar to Figs. VI and VII, illustrating a modification of the stationary refining member.

As illustrated in Figs. I and II, the general arrangement of the refiner resembles that illustrated in the above-mentioned Patent No. 1,984,869, but differs therefrom in particulars that make a brief general description desirable.

The refiner shown has coacting coaxially arranged refining members or discs 11, 12 enclosed in a housing 13 whose lower portion forms part of the main rigid (cast metal) base and frame structure 14 of the machine, while its upper portion may consist of a removable semi-cylindrical (sheet metal) cover 15. Preferably only one refining member 11 rotates, while the other member 12 remains stationary. Many methods of applying fluid pressure to the members 11, 12 (or their acting faces) and recording any increased 35 pressure due to pulp passing between the refining surfaces may be employed; but for purposes of illustration, the fluid pressure is here shown as applied to the stationary member, while the rotating disc is unyieldingly sustained by bearings 40 carried by the machine frame. As shown, the rotating refining member 11 may be mounted on the end of a shaft 16 which revolves in suitable (anti-friction) thrust and journal bearings 17, 17 in pedestal supports 18, 18 upstanding 45 from and forming part of the base structure 14, and is driven by a (variable speed) electric motor 19 also mounted on the base 14, preferably through suitably enclosed speed-reduction gearing 20. Suitable means to prevent pulp or air 50 leakage along the rotating shaft 16 may be provided, such as a stuffing box 21 on the lower portion of the housing 13 around the shaft.

The stationary refining member 12 may be mounted on the structure 14 in any suitable way, 60

to prevent it from turning while allowing it to shift (in an axial direction) toward or from the revolving member 11, relative to said structure 14. As shown, the stationary member 12 is 5 mounted on the end of a (hollow) shaft 22 longitudinally slidable in guide supports 23, 24 carried by the machine frame 14. The shaft 22 is anti-turningly engaged with the frame structure 14, as by means of keyway and feather arrangements 25 at one (at least) of the guide supports. The working faces 27, 28 of the refining members 11, 12 may be formed by separate detachable and renewable facings of natural or artificial stone, or of metal such as bronze, iron, or (stainless) steel—or even in some cases of elastic material like rubber. Their facial features may be of any suitable character; although I prefer acting faces such as disclosed in my pending application Serial No. 746,646, filed October 3, 1934, 10 now Patent No. 2,035,994, granted March 31, 1936. The fiber pulp may be supplied to the refining pass between the members 11, 12 via the tubular shaft 22, which opens centrally through the facing 27 of the stationary member 12, by means of 15 any suitable sliding connection (not shown) to the left-hand end of the tube 22. The pulp is preferably supplied under substantially constant pressure, as by the means described in my said application, or in the aforesaid Patent No. 30 1,984,869.

For the purposes of present invention, fluid pressure to sustain the axially movable member 12 and its acting face 27 may be applied to a pressure member 30 acting on the tubular shaft 22, here shown as a piston in a cylinder 31 attached to a bracket portion 32 of the frame structure 14. As shown, this piston 30 has peripheral packing rings to prevent leakage of pressure fluid past the piston. By admitting fluid under 35 pressure to one side or the other of piston 30 (and venting it from the opposite side), the member 12 can be moved toward or from the member 11. For a given "closing" pressure per sq. in. on piston 30, urging the members 11, 12 together, the working pressure per sq. in. between them will be inversely proportional to the effective area of piston 30 and the coacting areas of said members 11, 12. In general, a liquid such as water or oil is preferable as a pressure medium. As shown in Fig. I, the guide supports 23, 24 have clamp straps 33, 34 which can be tightened to grip the shaft 22 fast and immovable, thus fixing or setting the clearance between the members 11, 12.

As shown in Fig. I, a pressure gage or indicator 35 is connected into the cylinder 31 at the left-hand side of the piston 30, to show the closing pressure. This gage 35 may either be graduated to show pressures per sq. in. on piston 30, or to show corresponding working pressures per sq. in. between the refining members 11, 12. In addition, an indicator 36 may be operatively connected to the shaft 22 to show the gap or clearance between the acting faces of the members 11, 12: it may be graduated in any convenient units of measurement—such as thousandths or ten-thousandths of an inch, for example. Such an indicator 36 may be mounted on a bracket 37 carried by the clamp 34 of guide support 24, and may be actuated by an actuator screw 38 adjustable in a bracket arm on a clamp collar 39 fast on the shaft 22. By adjustment of the screw 38, the indicator may be set to read zero when the members 11, 12 are in actual contact under a suitable closing pressure on the

piston 30: e. g., a pressure corresponding to about 10 lbs. per sq. in. on the areas of members 11, 12 which coact in working the fiber pulp. This zero setting is of course made when neither pulp nor any other fluid is being admitted between the working faces of members 11, 12. 5

If desired, the pressure and clearance indicators 35, 36 may be of continuously recording types, so as to furnish complete records of mutually corresponding pressures and clearances 10 throughout the operation of the refiner.

A mode of operation of the refiner is as follows:

When the refiner is to be started up, water under pressure sufficient to separate the members 11, 12 to a clearance of about .01 in. (as shown by the indicator 36) is passed through the refiner via the shaft 22, while a convenient closing pressure is maintained on the piston 30. Ordinarily, the machine operates without any 20 disc-separating pressure on piston 30. The motor 19 is started, and the rotor 11 is brought up to normal running speed—such as 50 to 350 R. P. M., for example, according to the design of the refiner and the character of the stock to 25 be treated. Normal speed of the rotor 11 having been attained, the pulp or stock to be refined is started through the refiner under a suitable constant operating head or infeed pressure, and the water shut off. The closing pressure in cylinder 30 31 is modified as necessary to give a desired working clearance of from about .001 in. to .005 in. between the members 11, 12, as shown by the indicator 36.

The normal running speed and the pulp-feed 35 or infeed pressure are determined according to the desired throughput and degree of refining, and upon the following principles:

When the refiner is operating with the clamps 33, 34 loose, with a constant infeed pressure on 40 the stock, and with a definite closing pressure on the piston 30, the unitary rigid structure consisting of piston 30, shaft 22, and refining member 12 automatically assumes a position of equilibrium in which the total closing pressure-thrust on piston 30 balances the opposing total pulp-pressure thrust produced on the member 12 by the stock in the refining pass. In this stock between the members 11, 12, the centrifugal force and the initial infeed pressure produce 45 kinetic energy which is used up in friction with the members 11, 12, as well as pressure on the members 11, 12 tending to separate them. The closer the members 11, 12, the greater the friction, and vice-versa; and the greater the friction, the less the velocity and flow through the refining pass, and the greater the separating pressure, and vice versa. For given facial features of the refining members 11, 12, the degree 50 of refining of the stock put through the refiner depends on the clearance or gap between the members, while the throughput and capacity of the refiner depend on the speed of rotation and the infeed pressure. The speed and the infeed pressure, as already mentioned, also influence the 55 pressure in the stock between the members, and hence the clearance or gap for equilibrium. In the preferred practice of my invention, the closing fluid pressure and the pulp thrust are balanced with a clearance or gap corresponding to 60 the desired refinement of the pulp, and with a pulp-feed pressure and speed of rotation giving the desired throughput at this clearance.

When the desired gap or clearance between members 11, 12 as attained, the clamps 33, 34 may 75

be tightened on the shaft 22 to lock and hold the member 12 fixed during subsequent operation. Thus the movable member 12 is in effect secured to the frame structure 14; and so both the members 11, 12 are now engaged by parts associated with said structure 14 and are sustained thereby at the clearance or gap previously established, as already described—quite independently of any closing fluid pressure on the piston 30 opposing the pulp thrust, and even in the absence of any such pressure. This setting of the working clearance or gap need not be disturbed until or unless the essential conditions are changed for some reason—such as a change of the stock to be treated, of the desired degree of refining, of the infeed pressure, of the relative speed of rotation of the members 11, 12, or of the gap or clearance between the members 11, 12—which last naturally changes with wear on the facings 27, 27. The correctness of the setting may be checked from time to time by bringing the closing pressure in cylinder 31 to the value determined at the previous setting, and loosening the clamps 33, 34 and noticing whether this freeing of the parts 12, 22, 30 results in any change of the clearance or gap as shown by the indicator 36. When such change occurs, the gap as thus corrected may be reset by retightening the clamps 33, 34. When thus resetting the gap, the zero of indicator 36 may be readjusted as already described; or the reading of this indicator after resetting the gap may be taken, for reference when next rechecking. Ordinarily, the refiner may be expected to run about a week at a time before resetting becomes necessary.

Of course the refiner may if desired be operated with the clamps 33, 34 loose and a standard closing pressure on piston 30, thus automatically compensating for wear on the members 11, 12 as it occurs and maintaining a constant working clearance or gap between them.

In order to obtain a low freeness or a large amount of refining action at a single passage of the stock through the refiner, a close clearance between the members 11, 12 (about .002 in.) is necessary. Very small variations of the gap or clearance between the members 11, 12 materially affect the properties of the refined product. A change of .001 in. in this gap is sufficient to give a wide range of properties. Further refining accuracy may be obtained by closely regulating and controlling the pressure between the refining surfaces. Slight changes in the degree of refining may be produced by slightly changing the infeed pressure, with the clamps 33, 34 loose as above described.

If with a closing pressure of 100 lbs. per sq. in. on piston 30 (for example) and the clamps 33, 34 loose, the gap registers .002 in. on indicator 36 when sufficient water is passing through the refiner to keep the temperatures of the members 11, 12 down to about 160° F., and if escape of liquid from the closing side of piston 30 is cut off, the closing pressure on piston 30 will rise when pulp is turned into the refiner instead of water—according to the consistency of the pulp and the volume of it passing. This increased pressure will be shown on the indicator 35, and any slight concomitant increase in the clearance will be shown on indicator 36. Such increase in the reading of indicator 35 for operation with pulp over operation with water accurately indicates the pressure required by reason of work done on the fiber.

Fig. V is a fragmentary diagrammatic view

of a cylinder 31 with shaft 22 and piston 30, showing various pressure arrangements and connections. To permit equalization of pressure or transfer of fluid between the two sides of piston 30 (and yielding of the latter to the separating thrust between the members 11, 12), there is a by-pass connection 40 with a control and regulating valve 41. For supplying fluid under pressure at either side of piston 30, there is a pipe line 42 with control and regulating valves 43, 44. For venting fluid either side of the piston 30, there are pipes 45, 46 with control and regulating valves 47, 48. The pipe 42 has branches, with control and regulating valves 49, 50, to opposite sides of the piston 30. The pipe 42 is connected to the pressure side of a (gear) pump 51 supplied with oil or other liquid through a pipe 52, and also to a source of gas under pressure, such as a reservoir 53. Yet another branch of pipe 42 leads to a cylinder 54 with a piston 20 operable by a screw to force liquid into cylinder 31 or vent it therefrom. There are also cylinders 55, 56 with screw-operated pistons (similar to the cylinder 54) connected through control and regulating valves 57, 58 to opposite ends of cylinder 31, affording another means of forcing liquid under pressure into the cylinder, or venting it therefrom, to move the piston 30 either way. When the screws of both pistons 55, 56 are tightened up (with all possible outlets from cylinder 31 closed), the piston 30 and the whole member 12 are locked in fixed position, and the working clearance or gap is dead-set, just as if the clamps 33, 34 had been tightened. How the various instrumentalities of Fig. V can be operated to move the piston 30 as desired, or hold it stationary, will readily be apparent to those skilled in such mechanisms.

Fig. VI illustrates a different construction of the stationary refining member 12a, and another way of applying fluid pressure in connection with this member. As here shown, the acting face 27a of this member 12a consists of a flat (metal) ring axially movable in an annular cavity in the member, which also contains a fluid-tight flexible or elastic-walled annular pressure cell 60, more or less like the inner tube of an automobile tire. Thus the member 12a forms a cylinder, the ring 27a itself constitutes a piston; and the cell 60 serves as packing to prevent leakage of pressure fluid past the piston. The cell 60 (as well as the facing 27a) may be anti-turningly engaged with the inner and outer peripheries of the cavity in the member 12a, one mode of such engagement being illustrated in Fig. VII. Pressure fluid (either liquid or gas) is introduced into the cell 60 and vented therefrom through a tubular connection 61, to which a pressure indicator or gage 35a may be connected for the same purpose as the indicator 35 in Fig. I. In this way, the clearance or gap and the working pressure between the acting faces of the refining members 11, 12a can be varied and adjusted in about the same way as above described in connection with Figs. I-IV.

Fig. VIII illustrates a construction similar to that of Figs. VI and VII wherein the facing 27b is flexible or elastic and forms part of the wall of the pressure cell 60b, though much thicker than the rest of its wall. This pressure cell 60b may be of rubber construction like a single tube bicycle tire, with fabric reinforcement (like that of an automobile tire casing or of a disc for a flexible disc joint) in the facing 27b.

Fig. IX illustrates a similar construction ap-

plied to a revolving refining member 11c. Here the pressure connection extends (axially) through the revolving shaft, including a tube 6ic connected to a pressure indicator or gage 35c and to a supply of pressure fluid in a reservoir 64, with a control and regulating valve 65 interposed in the connection. In the refining member 11c, the pressure connection includes a bent tube 66 in a central cavity 67 that is normally closed off from access of pulp by a removable cover 68.

In Figs. V-IX, various parts and features are marked with the same reference characters as in Figs. I-IV—with an added letter where such distinction appears desirable—as a means of dispensing with repetitive description.

Having thus described my invention, I claim:

1. A method of gauging and setting the refining gap or working clearance between relatively revolving refining disc members which are mounted on a frame and between which fiber pulp is introduced under constant pressure; which method comprises leaving one of the disc members free to move relative to the frame, toward or from the other member, in the axial direction, while exerting on said movable member a definite closing fluid pressure that balances the pulp thrust tending to separate the members at a working clearance or gap corresponding to the desired refinement of the fiber pulp; allowing relative positions of equilibrium of the members to be attained under these opposing forces; and thereafter securing said axially movable member to the frame, and thus sustaining it therefrom, at the clearance or gap thus established, against pressure responsive separation from the other member, even in the absence of any closing fluid pressure opposing the pulp thrust.

2. In a refiner of the character described, the combination of coacting axially acting refining disc members revolving relative to one another and free for relative movement in the axial direction, with an associated structure relative to which the members revolve and move as aforesaid, and means for supplying and introducing fiber pulp between the disc faces under constant pressure; means for exerting on at least one of said members a definite closing fluid pressure that balances the pulp thrust tending to separate the faces; and means engaging said members and sustained by said structure to maintain the members at the clearance or gap thus established, even in the absence of any closing fluid pressure opposing the pulp thrust.

3. In refiner of the character described, the combination of a frame and coacting axially acting refining disc members, one revolving and one stationary carried by said frame, the active face of the stationary member being free for movement toward and from that of the revolving member; means for supplying and introducing fiber pulp between the disc faces under constant pressure; cylinder and piston means for exerting on the stationary refining member a constant closing fluid pressure balancing the pulp thrust tending to separate the disc faces; and means engaging said stationary refining member and sustained by said frame to maintain disc faces at a clearance thus established, independently of any closing fluid pressure on the piston.

4. In refiner of the character described, the combination of a frame and coacting axially acting refining disc members, one revolving and one stationary, carried by said frame, the stationary member being free for movement toward and from the revolving member; means for supplying

and introducing fiber pulp between the acting disc faces of said members under constant pressure; means for exerting on said stationary member a definite closing fluid pressure balancing the pulp thrust between said faces tending to separate the members; and clamp means carried by the frame for clamping said stationary member and holding it fixed in a position thus established, thereby preventing pressure-responsive movement thereof.

5. A refiner of the character described comprising in combination coacting axially acting refining disc members, one revolving and one stationary, the stationary member being free for movement toward and from the revolving member and including a hollow shaft for introducing fiber pulp between the acting disc faces of said members under constant pressure; cylinder and piston means associated with said shaft for exerting on said stationary member a constant closing fluid pressure balancing the pulp thrust between said faces tending to separate the members; and clamp means around said shaft for clamping said stationary member and holding it fixed in a position thus established, thereby preventing pressure-responsive movement thereof.

6. A fiber pulp refiner comprising relatively revolving coaxial refining members with opposed coacting working faces substantially parallel and enlarging outward around their axes, and traversed transversely of the circumferential direction of the relative movement of their said faces by the fiber stock being treated, at least one of said refining members having its working face movable in the axial direction toward and from the other member, and including means for applying sustaining fluid pressure behind said face to maintain it in effective coaction with said other member.

7. A fiber pulp refiner comprising relatively revolving coaxial refining members with opposed coacting working faces substantially parallel and enlarging outward around their axes, and traversed transversely of the circumferential direction of the relative movement of their said faces by the fiber stock being treated, at least one of said refining members having its working face movable in the axial direction toward and from the other member, and containing a fluid pressure cell for exerting behind said working face a pressure to maintain it in effective coaction with said other member.

8. A refiner of the character described comprising coacting relatively revolving axially acting refining disc members, one, at least, of said members having a substantially rigid acting face movable in the axial direction, and means for supplying elastic pressure fluid to said member behind its said movable face, to sustain the latter in coaction with the other member.

9. A refiner of the character described comprising coacting relatively revolving axially acting refining disc members receiving fiber pulp between them under constant pressure, and having substantially rigid acting faces free for relative movement in the axial direction toward and from one another; and a fluid pressure cell in at least one of said refining disc members for exerting on its acting face a constant axial closing pressure balancing the pulp thrust tending to separate the faces, so as to maintain between the faces a constant clearance corresponding to the desired refinement of the pulp fiber.
